No. 727,748.

PATENTED MAY 12, 1903.

H. R. COLE.
FIRE ESCAPE.

APPLICATION FILED JULY 31, 1902.

NO MODEL.

UNITED STATES PATENT OFFICE.

HERBERT R. COLE, OF MILLVILLE, NEW JERSEY.

FIRE-ESCAPE.

SPECIFICATION forming part of Letters Patent No. 727,748, dated May 12, 1903.

Application filed July 31, 1902. Serial No. 117,884. (No model.)

To all whom it may concern:

Be it known that I, HERBERT R. COLE, a citizen of the United States, residing at Millville, in the county of Cumberland and State 5 of New Jersey, have invented a new and useful Fire-Escape, of which the following is a specification.

This invention relates to fire-escapes of that class which may be designated as "portable," 10 the same being made of a size which enables them to be conveniently carried in a trunk or even in the pocket of a traveler, and which in the event of an emergency may be in a moment's time attached and utilized as a 15 means of escape from burning buildings.

My present invention has among its objects to provide a device of this class which shall occupy but very little space, in which a reel upon which is wound a sufficient length of rope 20 for ordinary emergencies shall be so arranged as to be under absolute control in the unwinding thereof by two sets of brake mechanism, one of which is automatic in its action, and in which provision shall be made 25 whereby the person using it may so attach it to his person as to prevent danger of slipping.

With these ends in view my invention consists in the improved construction, arrangement, and combination of parts, which will be 30 hereinafter fully described, and particularly pointed out in the claims.

In the accompanying drawings, Figure 1 is a perspective view of my improved fire-escape, 35 showing the same in position for use. Fig. 2 is a side view of the same. Fig. 3 is an end view. Fig. 4 is a detail view.

Corresponding parts in the several figures are indicated by like characters of reference.

The frame of my improved fire-escape, 40 which may be described as being mainly rectangular in shape, is composed of the side pieces 1 1 and cross or end pieces 2 and 3. To the lower end piece 3 is suitably attached, by 45 means of an eye 4, a chain or strap 5, the free end of which is provided with a snap-hook 6 or equivalent means of attachment to the eye 4, which will enable the said free end when 50 the chain or strap 5 is looped around the wrist of the person using the device to be quickly and reliably connected with the said

eye. Other means of attachment may obviously be used if found preferable. The sides 1 1 of the frame are provided with bearings for the shaft 7 of a reel or drum 8, which is 55 journaled between the said sides, and upon which the rope 9, usually a wire rope, is wound. One of the ends of the shaft 7 is extended beyond the frame and squared so as to be readily engaged by a crank, whereby the rope may be 60 wound upon the reel. This, however, is not absolutely essential.

The upper cross-piece 2 of the device is mounted loosely in the side pieces 1 1, so that it may freely turn therein. The said cross-piece 2 is provided at or near its center with a perforation 10, and the parts of the cross-piece adjacent to said perforation may be flattened, as shown at 11. This flattened portion may be omitted; but the edges of the 70 perforation should be smoothed or rounded, as shown at 12, so as to avoid injury by friction to the rope 9, which passes through said perforation. The cross-piece 2 is provided at the end thereof with a yoke 13, spanning one 75 of the side pieces 1 and having a link 14 attached thereto. This link is adapted to engage any one of a series of notches 15 in the edge of the side piece 1, thereby holding the cross-piece 2 securely at any position to which 80 it may be turned. Now it will be seen that when the said cross-piece is in what may be termed its "normal" position the perforation 10 therein is in a vertical position, thus permitting the rope 9 to pass freely therethrough 85 when unwound from the reel 8. When the cross-piece 2 is turned, so as to bring the perforation 10 out of a vertical plane, it will engage the rope 9 frictionally when it is being unwound, thus causing a greater or less degree 90 of resistance to the unwinding, according to the angle to which the perforation 10 has been set and at which it is retained by the link 14, engaging the notches 15. It will be seen that this device forms an automatic 95 brake, whereby the degree of resistance to the unwinding of the rope from the ground may be adjusted and regulated according to the weight of the person using the device. In addition to this automatic brake I provide a hand-operated brake consisting of a yoke 16, the ends of the arms of which are

journaled in the sides 1 of the frame slightly above the reel 8. The arms 17 of this yoke are slightly curved and flattened, so as to engage the heads or ends 18 of the reel, and the 5 central part of the yoke forms a handle, by means of which the brake may be grasped and operated by the person using the device.

Pivots mounted upon the cross-piece 3 is an arm 20, provided at its upper end with a 10 plurality of catches or ratchets 21, any one of which may be caused to engage the brake rod or handle 16, thereby keeping said brake automatically in engagement with the heads or ends 18 of the reel with any desired degree 15 of pressure, and thus making it unnecessary for the person using the device to exert a hand-pressure upon said reel. This device, however, is not an indispensable element of the improved fire-escape, which, when de- 20 sired, may be used without this attachment.

The rope 9 is provided at its free end with a hook 20, by means of which it may be very easily and quickly connected with any suitable point of attachment.

25 The operation of my invention will be readily understood from the foregoing description, taken in connection with the accompanying drawings. When an emergency arises, all that is necessary is to attach the hook at the 30 end of the rope to any sufficiently-secure point of attachment. The strap or chain 5 is then looped around the wrist of one hand, which grasps the cross-piece 3, and made fast by means of the snap or fastening device 6. The 35 link 14 is adjusted in one of the notches 15, so as to tilt the cross-piece 2 until the perforation 10 is set at a desired angle to insure the requisite degree of friction. The handle of the yoke or brake 16 is then grasped with 40 the other hand of the person using the device, who may now safely descend after passing through a window or other convenient exit. The rapidity of the descent may be absolutely controlled by means of the brake 16; but if 45 the person using the device should faint or lose self-control the rapidity of the descent will nevertheless be sufficiently checked by the automatic brake mechanism comprised by the perforated cross-piece 2 and the means 50 for adjusting the same to prevent injury to the person using the device.

It will be understood that the cross-piece 2, with its perforation 10, practically constitutes a movable rope-guide, which may be tilted to 55 various angles, thereby effecting a variable deflection of the engaged portion of the rope, and thereby providing for the adjustment of the degree of friction between the parts. The means herein described for retaining the said 60 rope-guide at the desired angle and other details of the device may be varied without departing from the spirit of my invention.

Having thus described my invention, I claim and desire to secure by Letters Patent 65 of the United States—

1. A fire-escape having a movable rope-guide capable of effecting a variable deflec-

tion of the engaged portion of the rope, and means for retaining the guide at different adjustments, substantially as set forth. 70

2. A fire-escape having an angularly-movable rope-guide capable of effecting a variable angular deflection of the engaged portion of the rope, and means for retaining the guide at different adjustments, substantially as set forth. 75

3. A fire-escape having a retarding device consisting of a rocking element provided with a running-guide for the rope, substantially as set forth. 80

4. In a fire-escape, the combination with a rope and dispensing means therefor of a tilting guide through which the rope extends, and retaining means consisting of a latch and a notched element co-operating therewith, substantially as set forth. 85

5. In a fire-escape, the combination of a frame having a top cross-piece capable of turning in its bearings and provided with a perforation, a reel journaled in said frame, a rope 90 wound upon said reel and extending through the perforation in the top cross-piece, and means for retaining the latter at various angles of adjustment, substantially as set forth. 90

6. In a fire-escape, the combination of a 95 frame a cross-piece journaled in said frame and having a perforation, a reel journaled in said frame, a rope wound upon said reel and extending through the perforated cross-piece, a yoke secured to the latter and spanning one 100 of the side pieces of the frame, a link connected with said yoke, and a series of notches in the edge of the side piece of the frame adapted to be engaged by said link, substantially as set forth. 105

7. In a fire-escape, the combination of a frame, a cross-piece journaled in said frame and having a flattened portion, a perforation extending through said flattened portion and having rounded edges, a reel journaled in the 110 sides of the frame, a rope attached to and wound upon said reel, extended through the perforated cross-piece and having means of attachment at its free end and means for retaining the perforated cross-piece at any position to which it may be turned with relation to the frame of the device for the purpose of regulating the degree of frictional contact between the perforation of said cross-piece and the rope passing therethrough, substantially as set forth. 115

8. In a fire-escape, the combination of a frame, a reel journaled therein, a perforated cross-piece, means for securing said cross-piece at any position to which it may be turned with relation to the frame, a rope attached to and wound upon the reel, extending through the perforated cross-piece and having means of attachment at its free end, a yoke having the ends of its arms journaled in the sides of 125 the frame above the reel, and with said arms curved and bearing against the heads of the reel, forming a brake, and flexible means for connecting the wrist of a person grasping the 130

lower cross-piece of the frame with said cross-piece, substantially as set forth.

9. In a fire-escape, the combination of a frame, a reel journaled therein and having a rope wound thereon and guided through a perforated tilting and adjustable cross-piece, a yoke forming a brake having the ends of its arms mounted in the sides of the frame, said arms engaging the heads of the reel and the 10 central part of the yoke forming a handle, a bottom cross-piece having means attached thereto for inclosing and securing the wrist of a person grasping said cross-piece, and an

arm mounted upon said cross-piece and having means for adjustably engaging the handle of the brake, thereby holding the latter automatically in engagement with the heads of the reel with any desired degree of pressure, substantially as set forth.

In testimony that I claim the foregoing as 20 my own I have hereto affixed my signature in the presence of two witnesses.

HERBERT R. COLE.
